HYDRAULIC CONTINUOUS PRESS

William C. Richardson, near Electra, Tex.

Application March 26, 1935, Serial No. 13,179

2 Claims. (Cl. 100—35)

This invention relates to a hydraulic continuous press, the general object of the invention being to provide upper and lower chains of the endless type, means for feeding the material to be pressed between the lower reach or stretch of the upper chain and the upper reach or stretch of the lower chain and applying pressure to the links of the lower stretch or reach of the upper chain whereby the material will be pressed between the upper reach of the lower chain and lower reach of the upper chain.

Another object of the invention is to so form the links of the lower chain that they will form a trough for the material being pressed by the upper chain and to provide an endless steel belt having perforations therein for registering with the perforations in the links of the chains and an endless strip of press cloth engaging the outer surface of the steel belt.

Another object of the invention is to subject the material at the front of the press to the pressure of a spring ram, after which the material is subjected to the pressure of hydraulic rams.

Another object of the invention is to provide supporting rolls for the upper reach of the lower chain and pressure rolls for the lower reach of the upper chain the latter rolls being carried by a frame which is engaged by the rams.

A still further object of the invention is to provide adjustable side rollers for engaging the sides of the links which form the trough.

This invention also consists in certain other features of construction and in the combination and arrangement of several parts, to be herein-after fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevation of the apparatus.

Figure 2 is an elevation with parts in section of the discharging end of the apparatus.

Figure 3 is a section on the line 3—3 of Figure 1.

Figure 4 is a fragmentary top plan view with parts omitted and parts in section.

Figure 5 is a section on the line 5—5 of Figure 2.

Figure 6 is a section on the line 6—6 of Figure 1 with parts shown in elevation.

Figure 7 is a section on the line 7—7 of Figure 2 with parts shown in elevation.

Figure 8 is a fragmentary sectional view on the line 8—8 of Figure 2.

Figure 9 is a fragmentary vertical sectional view through the adjacent reaches of the upper and lower chains.

Figure 10 is a side view of the front end portion of the frame which carries the pressure rollers engaged by the rams.

Figure 11 is a fragmentary top plan view of the steel belt.

Figure 12 is a top plan view of one of the links of the lower chain.

Figure 13 is a side view of said chain.

Figure 14 is a top plan view of the link of the upper chain.

Figure 15 is a side view of said link.

Figure 16 is a plan view of a link provided with a cutter.

Figure 17 is a side view of said link.

Figure 18 is a section on line 18—18 of Figure 1.

In these drawings the letter A indicates an upright supporting frame which rotatably supports the front and rear drums 1 and 2 for the lower chain B and the front and rear drums 3 and 4 for the upper chain C, one drum of each pair having its pintles carried by the adjustable bearing means shown generally at 5 for the front drum 1, in Figure 1, so that the tension of the chain can be adjusted. The links 6 of the lower chain are each formed of a plurality of longitudinally extending bars 7 having perforations 8 therein and provided with perforated ears 9 at their ends which receive the pivot pins 10 which pivotally connects the links together as shown more particularly in Figure 9 and each of these links 6, as shown in Figures 12 and 13, have bars 7' of considerable height at their sides so that each link is of substantially trough shape, the side bars 7' forming the sides of the trough. One end of each bar 7' is formed with a tongue 10' for fitting in a groove 11 of the next link and a tongue 10'' is formed on the upper or free edges of each bar 7'.

Each link 12 of the upper chain is formed in substantially the same manner as a link of the lower chain except that these links 12 are not provided with the high side bars 7' as are the links of the lower chain. A link of the upper chain is shown in Figures 14 and 15.

Figures 16 and 17 show a link 13 made in substantially the same manner as the link 12 excepting a transverse groove is formed in one face of the link for receiving a cutter bar 14 which is pressed outwardly by a spring 15 in the

groove. These links 13 can be substituted for the links 12 when desired.

The lower reach of the lower chain is supported by the rollers 16 and the upper reach of the upper chain is supported by the rollers 17 as shown in Figures 1 and 2.

An endless steel belt 18 and an endless strip of cloth or fabric 19 are provided for each of the upper and lower chains, the strip 19 contacts the outer face of the belt 18 and said belt is provided with perforations 20 which register with the perforations of the links, as shown in Figure 9, a portion of the belt being shown in Figure 11. By having the fibrous strips 19 covering the outer faces of the belts 18 the material to be pressed is contacted by said fibrous strips 19. Each set of belt and strip passes over a drum 21 supported at the discharge end of the machine and at the front or inlet end of the machine the belt and strip for the lower chain simply pass over the links of the chain as said links pass around the front roller 1. The belt and strip of the upper chain pass over a substantially arcuate shaped member 3' which surrounds the front portion of the upper roller 3 and is spaced therefrom to permit the chain to pass between itself and over or around the roller 3, as shown in Figure 1. As it will be seen the belt and strip of the lower chain rest in the bottom of the trough formed by the links of the chain while the belt and strip of the upper chain engage the outer surface of the links of said chain. Transverse supporting plates 22 are carried by the rear end of the frame in front of the drums 21 for supporting the upper reaches of the lower and upper sets of belts and strips.

A horizontal row of rollers 23 is provided for supporting the upper reach of the lower chain and a horizontal row of rollers 24 engages the links of the lower reach of the upper chain, these rollers 24 having their pintles rotatably arranged in the side bars 25 which at the front end of the apparatus are each provided with the pivoted sections 25' as shown in Figure 10, the pintles of some of these rollers 24 acting to pivot the sections to each other and to the main part of each side bar. Front and rear slotted brackets 26 are attached to the main frame and the pintles of the end rollers 24 pass into the slots 27 of these brackets as shown more particularly in Figure 5 and this arrangement permits limited vertical movement of the bars 25 and the rollers 24.

A spring ram 28 shown in detail in Figure 6 is supported from the main frame and engages the pivoted sections 25' of the side bars and tends to press said sections and the rollers carried thereby downwardly. As shown in Figure 6 this ram includes a socketed lower part 29 which contacts the sections 25' and the socket of which receives the head 30 of a bolt 31 which passes through a nut 32 attached to the frame. A spring 33 is partly located in the socket and engages the nut 34 on the threaded part of the bolt so that the tension of the spring 33 can be adjusted as well as the distance between the base part 29 and that part of the main frame which carries the nut 32. By adjusting the parts of the spring ram the amount of pressure with which the front links of the lower reach of the upper chain engages the material can be regulated.

Hydraulic rams 35 engage the main parts of the bars 25 to cause the links of the upper chain engaged by the rollers 24 carried by said parts 25 to engage the material being pressed and each

of these rams 35 comprises a cylinder 36 having a piston 37 therein the piston rod 38 of which is formed of two parts adjustably connected together as shown in Figure 7 with the lower end of the rod engaging the head 39 which rests on the bars 25 as shown more clearly in Figure 3. Fluid under pressure is simultaneously introduced into the top parts of the cylinders 36 by the pipe line 40 so that the hydraulic rams will exert uniform pressure upon the parts.

Alternate rollers of the lower row 23 are driven from a shaft 41 having the worms 42 thereon engaging the worm gears 43 on the pintles of said alternate rollers and alternate rollers of the upper row 24 are driven from a shaft 44 having worms 45 thereon engaging the worm gears 46 on the pintles of said alternate rollers. The shaft 41 has a pulley 47 on one end thereof and the shaft 44 has a worm gear 44' thereon which meshes with a worm 48 on a cross shaft 49 having a pulley 62 connected therewith, the pulleys 47 and 62 being belted to a suitable source of power. Thus these alternate rollers of the upper and lower rows 23 and 24 will drive the two chains and the belts 18 and the strips 19.

A hopper 48 is located at the front end of the machine and feeds the material to be pressed between the front ends of the upper reach of the lower chain and the lower reach of the upper chain, and as it will be seen in Figure 1 the front drum 3 of the upper chain is so located that the front end of the lower reach of said chain is spaced from the lower chain so that the material can pass between the two chains, after which it is pressed between the two chains, the belts 18 and the strips 19 by the pressure exerted by the spring and hydraulic rams.

A distributor 49, consisting of a roll provided with paddles is located in the hopper and is driven by a belt and pulleys shown generally at 40 50 from the front roller 23, as shown in Figure 1, and blades 51 are located at the rear end of the machine for scraping the pressed material from the strips 19 as also shown in Figure 1.

The side bars 1' of the links of the lower chain 45 have pressure applied thereto, as said links travel from the upper part of the drum 1 to the upper part of the drum 2, by the vertically arranged rolls 52 carried by channel members 53 located at the sides of the main frame and slidably supported for horizontal movement by the studs 54 carried by the brackets 55 attached to parts of the main frame. Bolts 56 pass through threaded holes in parts of the main frame and engage the members 53 to press the rolls 52 against the side 55 bars 1' of the links 6 as shown in Figure 3. These rolls 52 hold the links of the upper reach of the lower chain and the lower reach of the upper chain in position.

A moisture pan 57 is located under the upper 60 reach of the lower chain for receiving moisture from the pressed material and this pan is provided with a depending tube 58. I also provide a scraper 59 in the rear part of the hopper 48 which acts to evenly distribute the material passing from the hopper upon the front portion of the upper reach of the lower chain.

From the foregoing it will be seen that the two chains as well as the two steel belts and fabric belts are driven by the upper and lower 70 rollers 24 and 23, alternate ones of these rollers being driven with each driven roller of the upper row 24, being located directly above an undriven roller of the lower row 23. It will also be seen that the material is subjected to pressure first 75

5 by the spring ram and then by the hydraulic rams and that the material is subjected to pressure for a considerable distance as it travels with the moving parts from the hopper to the discharge end of the device. The side rolls 52 engaging the sides of the trough forming links of the lower chain effectively hold the links of the two chains while in pressing position in proper position.

10 It is thought from the foregoing description that the advantages and novel features of the invention will be readily apparent.

15 It is to be understood that changes may be made in the construction and in the combination and arrangement of the several parts, provided that such changes fall within the scope of the appended claims.

20 For instance, the hydraulic and spring presses can be replaced by air presses or the like and instead of having the chains perforated, they may be imperforated, or the lower chain may be perforated, and the upper chain imperforated. Also, when desired the fabric and steel belts can be omitted. Also, the blade bearing links, shown 25 in Figures 16 and 17, can be used in the upper chains. When this is done they will act as drag links, forcing the material through the machine under pressure. When such links are used, the pressure cloth and steel belts are omitted from 30 the upper chains.

The machine may be used for pressing fabrics, extracting oils from cotton and flax seeds and the like, and fruit and vegetables.

What is claimed is:—

35 1. A pressing machine of the class described comprising upper and lower endless chains, drums for supporting the chains, the links of the lower chain being of substantially trough shape in cross section, means for feeding material into 40 the trough of the upper reach of the lower chain at one end of the machine, the material discharging at the opposite end thereof, an endless perforated belt of metal, an endless fabric strip contacting the outer face of the belt, a set of these 45 belts being provided with each chain with each belt engaging the outer faces of the links of each chain, a drum for each set spaced rearwardly of the rear chain drum, the front ends of the sets 50 passing around the front chain drum with the links, the links of both sets of chains being perforated and the perforations registering with those in the belts, means for applying pressure to the lower reach of the upper chain and means for causing the chains to travel in their paths, said means including upper and lower horizontal 55 rows of rollers, the lower row engaging the links of the upper reach of the lower chain and the upper row engaging the links of the lower reach of the upper chain and means for rotating some of the rollers of both rows, said means including worm gears engaging alternate rollers, with the undriven rolls of the upper row placed over the driven rolls of the lower row, said pressure means including hydraulic rams for pressing the major part of the upper row of rolls downwardly and a spring ram for pressing the front rolls of the top row downwardly, said top row being supported for vertical movement by side bars supported for vertical movement, the front parts of the side bars being formed in sections pivotally connected with the major parts of the side bars with the spring ram engaging said sections.

5 lower reach of the upper chain and means for rotating some of the rollers of both rows, said means including worm gears engaging alternate rollers, with the undriven rolls of the upper row placed over the driven rolls of the lower row, said pressure means including hydraulic rams for pressing the major part of the upper row of rolls downwardly and a spring ram for pressing the front rolls of the top row downwardly, said top row being supported for vertical movement by side bars supported for vertical movement, the front parts of the side bars being formed in sections pivotally connected with the major parts of the side bars with the spring ram engaging said sections.

10 2. A pressing machine of the class described comprising upper and lower endless chains, drums for supporting the chains, the links of the lower chain being of substantially trough shape in cross section, means for feeding material into 15 the trough of the upper reach of the lower chain at one end of the machine, the material discharging at the opposite end thereof, an endless perforated belt of metal, an endless fabric strip contacting the outer face of the belt, a set of these 20 belts being provided with each chain with each belt engaging the outer faces of the links of each chain, a drum for each set spaced rearwardly of the rear chain drum, the front ends of the sets 25 passing around the front chain drum with the links, the links of both sets of chains being perforated and the perforations registering with those in the belts, means for applying pressure to the lower reach of the upper chain and means for causing the chains to travel in their paths, 30 said means including upper and lower horizontal rows of rollers, the lower row engaging the links of the upper reach of the lower chain and the upper row engaging the links of the lower reach of the upper chain and means for rotating some 35 of the rollers of both rows, said means including worm gears engaging alternate rollers, with the undriven rolls of the upper row placed over the driven rolls of the lower row, said pressure means including hydraulic rams for pressing the major part of the upper row of rolls downwardly and a spring ram for pressing the front rolls of the top row downwardly, said top row being supported for vertical movement by side bars supported for vertical movement, the front parts 40 of the side bars being formed in sections pivotally connected with the major parts of the side bars with the spring ram engaging said sections, and a pan located under the lower row of 45 rolls for receiving moisture from the pressed material.

50 WILLIAM C. RICHARDSON.
